UNITED STATES PATENT OFFICE.

FURN O. BROCKMAN, OF ROSEDALE, KANSAS.

DESIGN FOR A DOLL FIGURE.

54,888.

Specification for Design.

Patented Apr. 20, 1920.

Application filed November 1, 1919. Serial No. 335,179. Term of patent 3½ years.

To all whom it may concern:

Be it known that I, FURN O. BROCKMAN, a citizen of the United States, residing at Rosedale, in the county of Wyandotte and State of Kansas, have invented a new, original, and ornamental Design for a Doll Figure, of which the following is a specification, reference being had to the accompanying drawing, forming a part thereof.

In the drawing—

Figures 1 and 2 are front and side views, respectively, of a doll figure, showing my new design.

I claim:

The ornamental design for a doll figure, as shown.

FURN O. BROCKMAN.
